UNITED STATES PATENT OFFICE.

JOHN DYMOND, OF TORONTO, ONTARIO, CANADA, ASSIGNOR OF ONE-FIFTH TO JOHN DOUGLAS, OF VANCOUVER, BRITISH COLUMBIA, CANADA, AND THREE-TENTHS TO LOUISA E. WESTON, CARRYING ON BUSINESS UNDER THE FIRM-NAME AND STYLE OF WESTON & CO., OF TORONTO, ONTARIO, CANADA.

PIPE-ELBOW-BENDING MACHINE.

1,096,025.

Specification of Letters Patent.

Patented May 12, 1914.

Application filed May 16, 1913. Serial No. 768,042.

To all whom it may concern:

Be it known that I, JOHN DYMOND, of the city of Toronto, in the Province of Ontario, Canada, have invented certain new and useful Improvements in Pipe-Elbow-Bending Machines, of which the following is a specification.

This invention relates to machines for bending elbows for sheet metal pipes such as used in downflow pipes for eaves-troughing in which the interior must be comparatively smooth and my object is to devise a machine for this class of work which will be simple, strong and durable and which will produce substantially a perfect elbow.

I attain my object by means of the constructions hereinafter described and illustrated in the accompanying drawings in

Figure 1 is a front elevation of my improved machine; Fig. 2 is a side elevation of the same; Fig. 3 is a longitudinal section with parts broken away; Fig. 4 is an elevation partly in section showing the inner side of the head of the machine; Fig. 5 is an enlarged sectional detail illustrating the crimping of the pipe; Fig. 6 is a side elevation partly in section of the pipe elbow as formed by my machine; Fig. 7 is a front elevation, partly in section, of the feeder head; Fig. 8 is a rear elevation of the same; Fig. 9 is a plan view of part of the same showing particularly the clamping levers; Fig. 10 is a plan view showing the means for throwing the clutch of the machine out of engagement at the completion of an elbow; Fig. 11 is a rear end elevation of part of the machine showing the aforesaid clutch actuating means; Fig. 12 is a sectional detail showing the method of carrying the folder ring; Fig. 13 is a front elevation of the crimper knife adjustment.

In the drawings like numerals of reference indicate corresponding parts in the different figures.

1 is the frame of the machine suitably shaped to support the different parts. On this frame is suitably journaled the shaft 2, from which the movable parts of the machine are driven. This shaft is driven from the shaft 3 by means of the pinion 4 on the shaft 3 meshing with the gear wheel 5 loose

on the shaft 2 and adapted to be given a driving connection therewith by means of 55 the clutch 6, which may be of any suitable construction actuated in the ordinary manner by the shifter lever 7.

The operation of bending requires that a section of pipe be suitably held and intermittently fed forward. For this purpose I provide the feeder head 8, suitably carried on the longitudinal guides 9 (see particularly Figs. 2, 7 and 8). This head is provided at its under side with the ratchet rack 10, with which engages the dog 11, which is vertically slidable in the slide 12, movable longitudinally in the guides 13 (see Fig. 3). This slide is actuated by means of the rock arm 105 pivoted at 14, intermediate its ends 60 to the bracket 15, secured to the bed of the machine. The upper end of the arm engages the slide by means of a pin and slot connection to compensate for the angular movement of the rock arm, and the arm is provided at its lower end with an anti-friction roller 16 adapted to engage in the grooved cam 17 suitably figured to produce the desired rocking movement of the rock arm. The dog 11 is normally yieldingly pressed 70 upwardly by means of the spring 18. By the mechanism described the dog is intermittently reciprocated longitudinally of the machine, feeding forward the rack one tooth at a time and slipping back to reengage in a 75 new position.

The feeder head 8 is provided with the following means for holding and clamping the lengths of pipe. A sleeve 19 is supported longitudinally of the machine, being 80 connected at the rear of the machine to the rear head 20 and its forward end supported in the feeder head 8, which is slidable longitudinally on the sleeve, as well as on the guides 9. A collar 21 is formed 85 at the front of the feeder head and with this collar the clamp arms 22 are adapted to co-operate. These clamp arms are pivoted at their lower ends on a common pivot, 23, and their sides are so shaped that when their upper ends are brought together they will securely clamp a length of pipe against the collar 21. Their upper ends are actuated for this purpose by the levers 24, pivoted intermediate their ends and engaging the upper 90 ends of the said clamp arms (as shown par-

ticularly in Figs. 7, 8 and 9). The other ends of these levers 24 are adapted to be spread by means of the wedge 25, which is formed on the slide 26, vertically movable on the guide 27 extending upwardly from the feeder head. Secured to this guide is the upwardly extending screw 28, on which is screwed the hand wheel 106, the hub of which is provided with a flange 30 engaged with the notched fingers 31 secured to the slide 26. It is evident that by rotating the hand wheel 106 that the wedge 25 may be actuated to rock the levers 24 to actuate the clamp arms 22, and that by a reverse movement of the hand wheel the clamp arms may be released.

The operation of the machine demands that a central mandrel be employed to support the pipe and to carry and actuate a folder ring to hold down the crimped portions of the pipe as hereinafter described. This mandrel 32 is slidable within the sleeve 19 and extends through the rear end of the rear head 20. This mandrel is reciprocated by means of the rocking lever 33 connected with the mandrel by means of the pin and slot connection 34. This rocking lever may be actuated in any suitable manner from the cam shaft 2. I show for this purpose a rocking lever 35 having its lower end provided with anti-friction rollers 36 adapted to be engaged by the opposed cams 37 secured to the shaft 2. This rocking lever 35 is connected with the rocking lever 33 by means of the pivoted link 38. At the forward end the mandrel is provided with an enlargement 107 adapted to closely fit within the pipe (see particularly Figs. 3 and 5). Spaced from the end of the mandrel is a folder ring 39, the function of which is to fold down the crimps formed in the pipe, as indicated in Figs. 5 and 6. To enable the folder ring to accommodate itself to slight irregularities in the crimps I preferably give it freedom to rock slightly in any direction. For this purpose I connect it with the mandrel, preferably as follows: A disk with a segmental spherical projection 40 is fitted on the end of the mandrel and the folder ring 39 is suitably shaped to fit this projection. The outer side of the folder ring is also provided with a similar segmental spherical projection 41, concentric with the former. A screw 42 is formed at the end of the mandrel and the folder ring fits loosely thereon. (See Fig. 12.) A nut 43 is screwed on the screw 42 outside the folder ring and is preferably concaved to receive the segmental spherical projection 41, and a second or outer nut is also preferably provided to jam the former. By suitably adjusting the nuts the folder ring will be properly held in position while it is free to rock slightly in any direction as desired.

The operation of the machine, as so far

described, is as follows: With the parts in the position shown in Fig. 5 a crimp is formed in the pipe through means herein-after described, the crimped metal being forced into the space between the folder 70 ring and the enlargement 107. The mandrel is then retracted and the folder ring draws down and flattens out the crimps, as indicated in Fig. 6. As the crimps progressively decrease in depth from the throat 75 to the back of the pipe, the latter assumes the curved elbow form as desired. The pipe is suitably held, crimped and released to permit of the operation of the mandrel by the following means: At the front end 80 of the machine a clamping head or frame is provided having a central opening for the passage of the lengths of pipe. This head is formed in two parts, 44 and 45, suitably guided in the vertical guides 46. The 85 division between the two parts is horizontal and intersects the center of the opening therein. During the crimping operation the clamping head and the end of the mandrel are in substantial alinement, as shown 90 in Fig. 5. The opening is preferably provided with a special steel clamping ring also formed in halves and adapted to be removed for renewal or repairs. This clamping ring 47 is preferably divided horizontally and 95 the halves are fitted to a holder 48 by a suitable arrangement of grooves and projections, as shown in Fig. 5. The holder is similarly provided and fitted to the parts of the clamping head. It will be noted on 100 reference to Fig. 4 that the clamping ring 47 is eccentric to the enlargement 107 so that more space for clearance is provided at the throat of the elbow where the folds of metal require more room than the single thickness 105 at the back.

To actuate the clamping head I provide the following mechanism: On the cam shaft 2 is located an eccentric 49 connected with a cross head 50, connected with the connecting rods 51, passing through lugs 114 secured to the upper part 44 of the clamping head. A collar 115 secured on each connecting rod engages below the lug 114 and thus provides a connection whereby the part 110 44 of the head may be lifted. Nuts 116 are screwed on the ends of the connecting rods and are so spaced above the upper ends of the lugs 114 that as the connecting rods descend, the nuts only engage the lugs just at the end of their downward movement. Except just at this time there is, therefore, no positive clamping action of the clamping head except as herein-after described. This part of the head is 115 thus raised and lowered intermittently as the cam shaft rotates. The lower part 45 of the clamping head is provided with a projection 52 resting on the ends of the levers 53, fulcrumed intermediate their ends 120 125 130

on suitable fulcrums 117 on the bed of the machine, and pivotally connected with the lower ends of vertical rods 54 which extend upwardly to a suitable position to be engaged by the projecting portions of the upper part of the head 44. Adjusting screws 55 are preferably provided at the upper ends of the rods 54, so that the movements of the lower part 45 of the head may be accurately regulated to synchronize with that of the upper part. Instead of or in addition to the screws 55 I may make the fulcrum 117 adjustable to and from the projection 52. For this purpose I employ a right-and-left hand threaded screw 118 provided at its center with a collar 119 by means of which it may be rotated. The screw is threaded into the fulcrums and the collar held from endwise movement by being fitted into a notch 120 formed in a part of the frame of the machine. It will be evident that by turning the collar the fulcrums may be adjusted as desired. I also provide spring means tending to hold the upper part of the clamping head in its clamping position. For this purpose I provide pins 56 projecting upwardly from the guides 46 and having suitable nuts screwed on their upper ends. Coil springs 57 surrounding the pins engage the nuts and the upper side of the upper part 44 of the clamping head. Thus except when the upper part 44 of the clamping head is lifted as hereinbefore described a yielding clamping action is maintained on the pipe being bent except just as the crimping, herein-after described, is being completed when the clamping is made positive as hereinbefore described. During folding the clamping action is yielding which prevents the folding ring from breaking or tearing the pipe by catching on imperfections or roughnesses. The mechanism is so timed that the parts of the head are brought together to clamp the pipe on the enlargement 107 on the end of the mandrel 32 during the crimping operation, and to release the pipe after the folding operation, during which the mandrel end has to travel rearwardly within the pipe.

The crimping is done by means of four crimpler knives which are arranged at the front of the machine so as to move radially substantially on the diagonals of an imaginary square circumscribing the pipe and having one side tangential to the back of the pipe. The lower knives are movable on suitable guides 58 carried on the end of the machine. These lower knives comprise the backs 59 and the blades 60, which are separated by a wedge-shaped space in which a wedge 61 is adapted to reciprocate. This wedge is adjustable by means of a screw 62 engaging suitable lugs on the back 59 of the knife and on the wedge and actuatable in the

ordinary manner to adjust the position of the wedge. This enables me to accurately adjust the position of the edges of each of the lower knives. The upper knives 68 are movable on the lower knives preferably by being pivoted thereto. In the drawings I show each upper knife provided with an arm 67 pivoted at 69 on one of the lower knives. Each of the upper knives is provided with the inclined upper surface 70, adapted to engage a projection 71 on the end of the machine. Each projection 71 is preferably formed as an anti-friction roller, which for the purposes of adjustment is carried on the plate 72, formed as a lever of the first order, suitably fulcrumed on the frame of the machine and provided with the clamp nut and slot adjustment 73, whereby the plates may be adjusted to vary the positions of the projection 71 relative to the inclined surfaces 70. The result of this construction is that as the lower knives are raised the inclined surfaces 70, by their engagement with the projections 71, force the upper knives inwardly at the same time. These movements are so correlated that each of the four knives moves inwardly on a substantially radial line. The operative edges of the knives, it will be seen on reference to Fig. 1, form substantially a complete circle, but this circle is eccentric to the axis of the mandrel 32, so that a crimp is formed which is deepest at the throat of the pipe and dies away to nothing at the back thereof. To insure the proper crimping of the throat it is preferable that the lower blades slightly overlap, as shown.

Coil springs 74 secured to the upper knives and to the end of the machine serve to retract the upper knives as the lower knives are withdrawn through the action of the eccentric 63. It will be noted that for convenience in replacement the crimping blades 75 are made removable, being secured in place by means of the screws 76. The eccentric 63 is so timed that the crimping operation takes place during the time that the clamping head is clamping the pipe on the end of the mandrel 32.

The clutch is manually controlled by means of the lever 77 pivoted at a convenient point at the front of the machine. This lever, by means of the connecting rod 78, actuates the transverse rock shaft 79, which is provided with a suitable crank arm 80 to which the connecting rod is pivoted. This rock shaft has a second rock arm 81 secured thereto, connected by means of a connecting rod 82 to one end of a rocking lever 83, pivoted intermediate its ends to the frame of the machine and adapted to actuate the shifter lever 7 by means of the connecting rod 84. When the machine is to be stopped ready for the removal of a finished elbow it is desirable to automatically throw out the

dog 11. For this purpose I provide on the rock shaft 79 a rock arm 85, which is provided with a pin or other projection 86 adapted to engage a finger 87 projecting from the lower end of the stem of the dog 11. When the rock shaft is actuated in the operation of throwing out the clutch the pin engages the finger and draws the dog down out of engagement with the rack. As soon as the clutch is thrown in again the finger is, of course, released and the dog rises to its original position. See Fig. 3.

To enable the machine to automatically throw out the clutch as soon as an elbow is completed, thus stopping itself, I provide the following mechanism: A lever 88 is fulcrumed with its upper end just behind the rear end of the mandrel 32. A contact screw 89 provided with clamping nuts is screwed through the end of the lever and serves to adjust the gap between the lever and the mandrel. The lower end 90 of this lever is bent laterally to engage one end of a lever 91 fulcrumed intermediate its ends. The other end of this lever is pivotally connected with a looped link 94 hooking about a rock arm 92 secured to a crank disk 93 pivoted on the side of the machine. A connecting rod 95 is pivotally connected with a wrist pin on the disk and also with the arm 80 having operative connections with the clutch as hereinbefore described. Ordinarily as the mandrel reciprocates it does not touch the contact screw 89 but it is evident that if a part be moved between the two the rearward movement of the mandrel may be used to throw out the clutch. For this purpose I provide the block 96 on the arm 97 swung on the upper end of the lever 98 fulcrumed intermediate its ends. The lower end of this lever has an anti-friction roller 99 journaled thereon. This roller lies in the path of the inclined plane 100 carried on one arm of the bell-crank lever 101. The other arm of the lever 101 is connected by the link 102 with one arm of the bell-crank lever 103, the other end of which lies in the path of a pin 104 at the rear end of the rack 10. The last forward movement of the rack thus operates the lever 103 to move the block 96 between the end of the mandrel 32 and the contact screw 89 and the last rearward movement of the mandrel as it folds the last crimp throws the clutch out of gear through the connections already described.

As the dog 11 is automatically thrown out at the same time as the clutch 6, I find it necessary to provide means to prevent the head 8 being prematurely pushed back when released by the dog 11. For this purpose I provide the latch 108 pivoted on the head and adapted to automatically engage the catch 109 on the frame of the machine. The latch is provided with a tail 110 engageable by the pivoted lever 111. This lever is op-

erable by the connecting rod 112 from the foot lever 113 which thus provides means whereby the operator can conveniently release the head when the machine comes to rest and the elbow is removed. It is also desirable to provide means for adjustably determining the rearward position of the feeder head so that when shifted back it will come to the same position every time without special attention on the operator's part. For this purpose I provide the screw stop 121 screwed through the lug 122 on the frame of the machine. A lug 123 is formed on or secured to the feeder head 8 in a position to engage the screw stop 121. This stop is set according to the length of the pipes to be bent so that after each elbow is completed it is merely necessary to push back the feeder head till it is stopped by the screw 121.

What I claim as my invention is:

1. In a pipe elbow machine the combination of a movable feeder head; means for intermittently moving the same; means for clamping a length of pipe thereto; a longitudinally movable mandrel supported and proportioned to fit closely within a length of pipe when the latter is clamped to the head; a frame having an opening therein through which said length of pipe may pass; means for reciprocating the mandrel to bring it into or out of co-operative relationship with the frame; a folder ring connected with the end of the mandrel by means of a ball and socket joint whereby it may rock freely in any direction and separated from said mandrel end by a groove; radially movable crimpler knives; and means for moving said knives to crimp the wall of the pipe into the space between the mandrel and folder ring.

2. In a pipe elbow machine the combination of a movable feeder head; means for intermittently moving the same; means for clamping a length of pipe thereto; a longitudinally movable mandrel supported and proportioned to fit closely within a length of pipe when the latter is clamped to the head; a frame having an opening therein through which said length of pipe may pass; means for reciprocating the mandrel to bring it into or out of co-operative relationship with the frame; a folder ring connected with the end of the mandrel and separated therefrom by a groove; radially movable crimpler knives; means for moving said knives to crimp the wall of the pipe into the space between the mandrel and the folder ring; a shaft adapted to drive and time the various actuating means; driving means for the shaft; a clutch for putting the shaft into and out of gear with the driving means; means normally inoperative whereby the reciprocation of the mandrel may throw the clutch out of gear; and means actuated by

the feeder head adapted to condition the clutch shifting means for operation by the mandrel when the feeder head reaches its limit of forward movement.

5. 3. In a pipe elbow machine the combination of a movable feeder head; means for intermittently moving the same; means for clamping a length of pipe thereto; a longitudinally movable mandrel supported and proportioned to fit closely within a length of pipe when the latter is clamped to the head; a frame having an opening therein through which said length of pipe may pass, said frame being divided substantially on a plane intersecting the center of said opening; means for reciprocating the mandrel to bring it into or out of coöperative relationship with the frame; means for spreading and contracting the parts of the frame to closely embrace the pipe on the mandrel or to release the same; spring means tending to move the parts of the frame to embrace the pipe; a folder ring connected with the end of the mandrel and separated therefrom by a groove; radially movable crimper knives; and means for moving said knives to crimp the wall of the pipe into the space between the mandrel and folder ring.

4. In a pipe elbow machine the combination of a movable feeder head; means for intermittently moving the same; means for clamping a length of pipe thereto; a longitudinally movable mandrel suitably supported and having an end proportioned to fit closely within a length of pipe when the latter is clamped to the head; a frame having an opening therein through which said length of pipe may pass, said frame being divided substantially on a plane intersecting the center of said opening; means for reciprocating the mandrel to bring it into or out of coöperative relationship with the frame; means for moving each of the parts of the frame to embrace or release the pipe on the mandrel; a folder ring connected with the end of the mandrel and separated therefrom by a groove; movable crimper knives; and means for moving the said knives to crimp the wall of the pipe into the space between the mandrel and the folder ring, the opening in the frame when the parts are closed to embrace the pipe being eccentric to the folder ring and mandrel end to give more space at the throat of the pipe than at the back.

5. In a pipe elbow machine the combination of a movable feeder head; means for intermittently moving the same; means for clamping a length of pipe thereto; a longitudinally movable mandrel supported and proportioned to fit closely within a length of pipe when the latter is clamped to the head; a frame having an opening therein through

which said length of pipe may pass; means for reciprocating the mandrel to bring it into or out of coöperative relationship with the frame; a folder ring connected with the end of the mandrel and separated therefrom by a groove; radially movable crimper knives; means for moving said knives to crimp the wall of the pipe into the space between the mandrel and the folder ring; a shaft adapted to drive and time the various actuating means; driving means for the shaft; a clutch for putting the shaft into and out of gear with the driving means; means normally inoperative whereby the reciprocation of the mandrel may throw the clutch out of gear; and means actuated by the feeder head adapted to condition the clutch shifting means for operation by the mandrel when the feeder head reaches its limit of forward movement; and means for disengaging the means for moving the feeder head by the action of the clutch shifting mechanism.

6. In a pipe elbow machine the combination of a movable feeder head; means for intermittently moving the same; means for clamping a length of pipe thereto; a longitudinally movable mandrel supported and proportioned to fit closely within a length of pipe when the latter is clamped to the head; a frame having an opening therein through which said length of pipe may pass; means for reciprocating the mandrel to bring it into or out of coöperative relationship with the frame; a folder ring connected with the end of the mandrel and separated therefrom by a groove; radially movable crimper knives; means for moving said knives to crimp the wall of the pipe into the space between the mandrel and the folder ring; a shaft adapted to drive and time the various actuating means; driving means for the shaft; a clutch for putting the shaft into and out of gear with the driving means; means normally inoperative whereby the reciprocation of the mandrel may throw the clutch out of gear; and means actuated by the feeder head adapted to condition the clutch shifting means for operation by the mandrel when the feeder head reaches its limit of forward movement; means for disengaging the means for moving the feeder head by the action of the clutch shifting mechanism; and a latch adapted to automatically lock the feeder head against backward motion when the feeder head reaches its limit of forward movement.

Dated at Toronto this 3rd day of May 1913.

JOHN DYMOND.
